[57] CLAIM

The ornamental design for an ergonomic knife handle, as
shown and described.

DESCRIPTION

FIG. 1 is a front elevation view of an ergonomic knife handle, showing my new design, wherein the broken line
portions of the drawing are for illustrative purposes only and
form no part of the claimed design, the rear elevation being
a mirror image thereof;FIG. 2 is a top plan view of the ergonomic knife handle of
FIG. 1, the bottom being a mirror image thereof;FIG. 3 is a left end elevation of the ergonomic knife handle
of FIG. 1;FIG. 4 is a right end elevation of the ergonomic knife handle
of FIG. 1;FIG. 5 is a sectional view as taken on line 5—5 of FIG. 1 to
more clearly show certain ornamental features of the ergo-
nomic knife handle of FIG. 1;FIG. 6 is a sectional view as taken on line 6—6 of FIG. 1 to
more clearly show certain ornamental features of the ergo-
nomic knife handle of FIG. 1; and,FIG. 7 is a sectional view as taken on line 7—7 of FIG. 1 to
more clearly show certain ornamental features of the ergo-
nomic knife handle of FIG. 1 and with portions thereof
omitted for clarity.
